(57) **CLAIM**

The ornamental design for a screw on paint pole pull end, as shown.

DESCRIPTION

FIG. 1 is a front and right-side perspective view of a screw on paint pole pull end, embodying the new design; FIG. 2 is a front elevation view thereof; FIG. 3 is a rear elevation view thereof; FIG. 4 is a left-side elevation view thereof; FIG. 5 is a right-side elevation view thereof; FIG. 6 is top plan view thereof; FIG. 7 is a bottom plan view thereof; and, FIG. 8 is a bottom and right-side perspective view thereof. The broken line showing of the paint pole in FIG. 1 is provided for purposes of environment and forms no part of the claimed design.
